[57] **ABSTRACT**

A track lining tool, which is hydraulically movable laterally to move a track engaged by the tool, comprises a flanged wheel running on the top surface of the rail head, and another rail engaging element adjacent the wheel which can be moved into and out of a position wherein it engages the side surface of the rail head.

TRACK LINING APPARATUS

The present invention relates to a hydraulically operable track lining apparatus mounted on a mobile track liner for laterally moving a track.

It has been proposed to provide such apparatus with a rail engaging element rollingly or glidingly engaging the top surface of the rail head for one rail or both rails or a track to be lined, and an element engaging the side surface of the rail head for transmitting the lateral moving force to the rail or rails. For instance, flanged wheels have been used for this purpose, the wheels having either one or two flanges engaging one or both side surfaces of the rail head.

It is the primary object of this invention to provide a track lining apparatus of this general type which is also useful in track sections where it is difficult to engage the side surfaces of the rail heads, such as switch points, crossings and the like.

The above and other objects are accomplished in accordance with the invention with a track lining apparatus which comprises a first rail engaging element, such as a wheel which may or may not have a flange, which element rollingly or glidingly engages the top surface of the rail head of a rail of the track to be lined, and a second rail engaging element laterally adjacent the first rail engaging element for engaging a side surface of the rail head. The second element is mounted for adjustment in respect of the first element and is movable into and out of a position wherein it engages the side surface of the rail head.

The arrangement of the adjustable second rail engaging element may take a great variety of forms dependent solely on the requirements of the particular track formation. For instance, a pair of such elements may be mounted laterally adjacent the first rail engaging element for movement into and out of a position wherein a respective second rail engaging element engages a respective side surface of the rail head, as required by the direction of lateral movement, while the other element may be moved out of the engaging position because of lack of space at the point of engagement. The engagement with the side surface of the rail head of one of the second rail engaging elements will still make it possible to move the rail laterally in the desired position.

While the second rail engaging element may be pivoted or laterally moved out of the rail head engaging position, it is vertically movable into and out of this position in the preferred embodiment of the invention.

It is desirable for the lateral force transmitting, second rail engaging element to take up as little space as possible, preferably not substantially more space than the flange of a flanged wheel. Thus, the second rail engaging element may be a frusto-conical member rotatably mounted on an end of a rod mounted for vertical movement, the rotatable member conformingly engaging the oblique surface of the rail head which is conventionally of trapezoidal cross section. If desired, the second rail engaging element may instead be fixed about its vertical axis and be provided with a friction-reducing means, such as rollers, for engagement with the side surface of the rail head.

The adjustment of the second rail engaging element is preferably remote controllable so that its adjustment may be effected without loss of time. A cylinder-and-piston drive for the adjustment is useful.

While a pair of second rail engagement elements may be mounted for selective engagement with one or the other side surface of the rail head for operation of the apparatus in a selected lateral direction, it is also possible to mount a pair of these elements laterally adjacent one or each side of the rail head, the first rail engaging element being positioned intermediate or centrally between the pair or pairs of second rail engaging elements. If the first rail engaging element is a flanged wheel, with the flange of the wheel engaging one side surface of the rail head, a pair of the second rail engaging elements may be mounted for engagement with the other side surface of the rail head.

Whatever the particular arrangement of the rail engaging elements, it is useful to mount the track lining apparatus as a unit on the mobile frame of the machine on a pivotal carrier.

The above and other objects, advantages and features of the present invention will become more apparent from the following detailed description of certain now preferred embodiments thereof, taken in conjunction with the accompanying drawing wherein

FIG. 1 is a schematic side view of a generally conventional combined track lining and leveling machine;

FIG. 2 is a similar view of a different type of track lining and leveling machine;

FIGS. 3 and 4 are front elevational views of two embodiments of the track lining apparatus of this invention; and

FIGS. 5 and 6 are respective top views of FIGS. 3 and 4.

Referring now to the drawing and first to FIG. 1, there is shown a mobile track leveling and lining machine comprising an elongated machine frame 1 moving on the track rails 3, 3 on wheels 2, 2. The track rests on ties 4. An overhanging front portion of the machine frame carries a conventional vertically movable track leveling apparatus 5 and two groups of tamping tools 6 arranged to tamp simultaneously two adjacent ties and thus to fix the leveled track in position.

A track lining apparatus 7 is mounted on the machine frame 1 between the front and rear wheels 2, 2. Hydraulic motors 8 enable the track lining apparatus to be lifted off the track, when required to avoid obstacles on the track or when no track lining is desired or required. During lining operations, the track lining apparatus engages at least one rail of the track so that a horizontal, laterally directed, hydraulically operated force exerts a corresponding lateral pressure on the engaged rail or rails to move the track laterally.

As pointed out hereinabove, the present track lining apparatus is used with particular advantage in machines which operate at switch points, rail crossings and the like, and FIG. 2 illustrates such a track liner in which a machine frame 1' moves on wheels 2', 2'. An overhanging front portion of the machine frame carries tamping tools 6' and the operator's station 9, as well as a vertically movable carrier 5' pivotally mounted on the machine frame for holding the track engaging apparatus 7'. In this manner, the apparatus 7' may not only be lifted off the track but may also be used for leveling if the rail engaging elements grasp the rail heads during vertical movement.

All of the hereinabove described and illustrated structure is conventional. Two embodiments of the

track lining apparatus usable in such structures according to the present invention are shown in FIGS. 3 to 6. Both embodiments comprise hydraulically movable rail engaging means for selectively moving the track in one or the other lateral direction, the hydraulic motor used for this purpose being entirely conventional. In each embodiment, one rail engaging element rollingly engages the top surface of the rail head of a rail 3 of the track and at least one other rail engaging element is arranged to engage a side surface or flank of the rail head to transmit the lateral force to the rail.

Referring now to the embodiment shown in FIGS. 3 and 5, the first rail engaging element is a flanged wheel 10 having a flange 10' engaging one side surface or flank of the rail head of rail 3. The second rail engaging element is a vertically movable member 11 whose lower end carries a freely rotatable frusto-conical roller 11' for conforming engagement with the other oblique side surface of the rail head. The member 11 moves in a vertical guide 12 which, in the illustrated embodiment, is a cylinder. A pressure fluid supply is connected to the cylinder 12 at 13 for moving the member 11 into and out of a rail engaging position, the member 11 being the movable part of the cylinder-piston drive.

The axle 10" of flanged wheel 10 and the cylinder 12 of the rail engaging member 11 are mounted on carrier 14 which is pivotally mounted on machine frame 1. The hydraulic motor 8 or 8' presses the first rail engaging element 10 into rolling engagement with the top surface of the rail head so as to prevent disengagement of this element from the rail head during the lining operation.

As shown in FIG. 5, a pair of second rail engaging element 11 are mounted laterally adjacent the first rail engaging element 10 for movement into and out of a position wherein a respective member 11 engages the side surface of the rail head opposite to the side surface engaged by flange 10' of wheel 10. As shown, the flanged wheel is intermediate the pair of second rail engaging elements, i.e. these elements are symmetrically arranged on either side of wheel axle 10". As shown in FIG. 5, where another rail 3' at a switch point or crossing makes it impossible to move both rail engaging element 11, 11 into rail engaging position, one of them will be moved down into such position. This will suffice to engage the rail 3 and to exert the required lateral pressure thereon to move the same laterally. The vertical axes of the vertically adjustable rail engaging elements 11 extend between the plane of pivoting of carrier 14 and the plane of the wheel 10.

The embodiment of FIGS. 4 and 6 is similar in many respects to the above-described embodiment and to avoid redundancy in the description, like parts functioning in a like manner are designated by like reference numerals in both embodiments.

In this embodiment, the second rail engaging element 11a is a freely rotatable, vertically movable rod whose lower end is frusto-conical, thus functioning in the same manner as the freely rotatable roller 11'. The first rail engaging element is a flangeless wheel 15 running on the top surface of the rail head, and two pairs of the second rail engaging elements 11a are mounted laterally adjacent the wheel 15 for selective movement into and out of a position wherein a respective one or a respective pair of the second rail engaging

elements 11a engages a respective one of the side surfaces of the rail head so that the rail will be effectively gripped for lateral movement into a selected direction. The four elements 11a are mounted on brackets 16, 16 holding the cylinders for the elements 11a.

As shown in FIG. 4, at a switch point which includes the rail 17, the rail engaging elements 11a on one side of the rail 3 will be moved upwards from a rail engaging position (shown in broken lines) to an inoperative position (shown in full lines).

Many modifications and variation of structural details may occur to those skilled in the art, particularly after benefiting from the present teaching, without departing from the spirit and scope of this invention as defined in the appended claims.

What is claimed is:

1. A hydraulically operable track lining apparatus mounted on a mobile track liner for laterally moving a track, said lining apparatus comprising
  1. a first rail engaging element rollingly or glidingly engaging the top surface of the rail head of a rail of said track, and
  2. a second rail engaging element mounted for vertical adjustment in respect of the first rail engaging element and vertically movable into an operative position wherein it laterally engages one side surface of the rail head adjacent the first rail engaging element for exerting a lateral track moving pressure against the one rail head side surface, and into an inoperative position wherein the second rail engaging element is above the rail head and out of engagement with the one rail head side surface.
2. The track lining apparatus of claim 1, wherein the second rail engaging element is a frusto-conical member conformingly engageable with the one side surface of the rail head which is oblique and rotatable about a vertical axis.
3. The track lining apparatus of claim 1, wherein the second rail engaging element is a member rotatably mounted on an end of a rod mounted for vertical movement.
4. The track lining apparatus of claim 3, wherein the rotatably mounted member is frusto-conical and is conformingly engageable with the one side surface of the rail head which is oblique.
5. The track lining apparatus of claim 1, further comprising a support for the first rail engaging element, and a substantially vertical guide for vertically movably mounting the second rail engaging element; the vertical guide being affixed to the support.
6. The track lining apparatus of claim 5, wherein the guide is a cylinder and the second rail engaging element is movable in the cylinder, a pressure fluid supply being connected to the cylinder for moving the second rail engaging element.
7. The track lining apparatus of claim 1, wherein a pair of said second rail engaging elements are mounted laterally adjacent the first rail engaging element for movement into and out of a position wherein a respective one of the second rail engaging elements engages a respective one of the side surfaces of the rail head.
8. The track lining apparatus of claim 1, wherein a pair of said second rail engaging elements are mounted laterally adjacent the one side surface of the rail head, the first rail engaging element being positioned intermediate the pair of second rail engaging elements.

9. The track lining apparatus of claim 1, wherein the first rail engaging element is a wheel engaging the top surface of the rail head, and two pairs of said second rail engaging elements are mounted laterally adjacent the wheel for movement into and out of a position wherein a respective ones of the second rail engaging elements engages a respective one of the side surfaces of the rail head, with the wheel being centered between the second rail engaging elements. 5

10. The track lining apparatus of claim 1, wherein the first rail engaging element is a flanged wheel, the flange of the wheel engaging the other side surface of the rail head for holding the head between the wheel flange and the second rail engaging element when the latter is in the operative position. 10

11. The track lining apparatus of claim 10, wherein two of said second rail engaging elements are mounted on respective sides of the first rail engaging element. 15

12. A hydraulically operable track lining apparatus mounted on a mobile track liner for laterally moving a track, comprising 20

1. a flanged wheel rollingly engaging the top surface and one of the side surfaces of the rail head of a rail of said track,
2. a pair of rail engaging elements each mounted for 25 adjustment in respect of the flanged wheel,

a. the flanged wheel being positioned intermediate the pair of rail engaging elements,

3. a support for the flanged wheel,

4. a pair of vertical guide cylinders affixed to the support and vertically movably mounting the rail engaging elements into an operative position wherein a respective one of the rail engaging elements engages the other side surface of the rail head for holding the rail head between the flanged wheel and the rail engaging element or elements, and into an inoperative position wherein a respective one of the rail engaging elements is out of engagement with the other side surface of the rail head, and

5. a pressure fluid supply connected to the cylinders for moving the respective rail engaging elements vertically therein.

13. The track lining apparatus of claim 12, wherein the rail engaging elements are members mounted for rotation about a vertical axis for rolling and conforming engagement with the other side surface of the rail head in the operative position, and further comprising a rod mounted for vertical movement in each cylinder, each rotational member being affixed to an end of the rod. 20
